CLAIM

We claim the ornamental design for an electronic device, as shown and described.

DESCRIPTION

FIG. 1 is a front perspective view of an electronic device showing our new design according to a first embodiment;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a front view of an electronic device showing our new design according to a second embodiment;
FIG. 9 is a front view of an electronic device showing our new design according to a third embodiment;
FIG. 10 is a front view of an electronic device showing our new design according to a fourth embodiment;
FIG. 11 is a front view of an electronic device showing our new design according to a fifth embodiment;
FIG. 12 is a front view of an electronic device showing our new design according to a sixth embodiment;
FIG. 13 is a front view of an electronic device showing our new design according to a seventh embodiment;
FIG. 14 is a front view of an electronic device showing our new design according to an eighth embodiment;
FIG. 15 is a front view of an electronic device showing our new design according to a ninth embodiment; and,
FIG. 16 is a front view of an electronic device showing our new design according to a tenth embodiment.

The broken lines in the figures depict portions of the electronic device which form no part of the claimed design.

(Continued)

The rear, left-side, right-side, top and bottom views of the second through tenth embodiments of the electronic device depicted in FIGS. 8 through 16 have been omitted because they are exact duplicates of the same views of the electronic device design that are depicted in FIGS. 3 through 7.
